Primary Examiner — Mark Goodwin(74) *Attorney, Agent, or Firm* — Harness, Dickey & Pierce, P.L.C.(57) **CLAIM**

The ornamental design for a blower wheel disc, as shown and described.

DESCRIPTION

FIG. 1 is a perspective side view of a blower wheel disc showing our new design;

FIG. 2 is a perspective side view of the invention;

FIG. 3 is a bottom view of the invention;

FIG. 4 is a side view of the invention;

FIG. 5 is a side view of the invention;

FIG. 6 is a side view of the invention;

FIG. 7 is a side view of the invention; and,

FIG. 8 is a top view of the invention.
